UNITED STATES PATENT OFFICE.

WENDELL D. MYRES, OF NILES, OHIO.

VOUCHER-CHECK.

1,082,702.

Specification of Letters Patent. Patented Dec. 30, 1913.

Application filed February 11, 1913. Serial No. 747,630.

To all whom it may concern:

Be it known that I, WENDELL D. MYRES, a citizen of the United States, residing at Niles, in the county of Trumbull and State 5 of Ohio, have invented new and useful Improvements in Voucher-Checks, of which the following is a specification.

My invention relates to voucher checks and its object is to provide an instrument 10 of this nature which may be folded and sealed to conceal matter contained on one face thereof and which, when folded and sealed, presents on one face thereof a check, draft, order, or the like and on the other 15 face thereof a space for indorsements.

More specifically my invention comprises an instrument of the character described, provided with means for affording ready access to the concealed matter.

20 Other minor objects will appear herein-after.

Referring to the accompanying drawing, Figure 1 shows that face of the instrument which contains the matter to be concealed; 25 and Fig. 2 shows the reverse face of the instrument.

The matter to be concealed is shown on Fig. 1 as a voucher, containing on its upper portion certain indicia and ruled lines for 30 identifying the parties to the account and their addresses. To illustrate the words, "The Southern Steel Company, Largo, Ga.", indicate the party owing the account. The line following the words, "In favor 35 of", is for the party to whom the account is owed, his address to be written on the line following the word, "Address". The central portion of the voucher is ruled for the date, the items, the amounts of the items, 40 and the total thereof, this portion with the upper portion constituting a statement of account. The lower portion contains words vouching the correctness of the account and the purpose for which the expense covered 45 by the account was incurred. Suitable ruled lines are provided for the signatures of the auditor and treasurer or other officers, whose titles are indicated below the said lines. The voucher is folded lengthwise 50 midway between the top and bottom edges, along the line 1 which may or may not be placed on the vouchers. The front face of the instrument is reserved for the check, draft, order, or the like, and the indicia and

space for indorsements. 2 designates the 55 checks, draft, order, or the like directing a designated depository to pay the sum of money due on the said account, to the person, firm or corporation to whom it is due. This portion 2 occupies the upper half. 60 The remaining or lower half 2 contains suitable indicia and a space for indorsements of the payee and subsequent holders thereof. This portion may also contain a receipt by the payee for the payment of the account. 65 A narrow strip 4 along one of the side edges of the voucher face and thence along the ends thereof to the line 1, that is, to the center of the ends, is provided with an adhesive, such, for example, as is used for the 70 sealing of envelops.

The drawing shows a convenient form for applying the principle of my invention, made for the payment of a month's salary. It may be assumed that the payer and payee 75 do not desire to disclose the salary of the payee to the banking establishment at which the payee wishes to deposit the voucher check or to the several indorsers through whose hands the same may pass subsequently 80 to the payee's indorsement. The payee obeying suitable instructions, such as are shown at 5, placed on the reverse or voucher side of the instrument, folds the same along the line 1 or along the place 85 where the line 1 is shown, matches the lower edge and the lower ends of the side edges with the edges on the upper portion provided with the adhesive, and seals the matched edges in the usual manner of sealing 90 an envelop. Having done this, the check 2 will be upon one side of the folded sheet and the space for indorsements will be upon the opposite side thereof, the check and indorsement space occupying the same 95 relative places that they do on ordinary commercial paper.

Upon the return of the sealed voucher check to the drawer's or maker's office the margin may, in case it is desired to inspect 100 the voucher portion, be cut off within the adhering edges, or the same may be torn off along the perforated or weakened lines 6, if it is preferred to employ the same.

While I have suggested an adhesive such 105 as is used on envelops for sealing the voucher, I do not desire to be restricted to such sealing means as there are many other

kinds of adhesive material and many other kinds of sealing devices which may be used in place of the adhesive suggested.

I claim—

- 5 1. The combination with a negotiable instrument on one half of the front of a sheet of paper and a space suitably indicated for indorsements on the remaining half of the front thereof, of a statement of account on which the instrument is based on the reverse side of the sheet, means for sealing the edges of the two halves of the statement of account face to face, the statement of account being folded between the said check and space for indorsements.
- 10 2. The combination with a negotiable instrument on one half of the front of a sheet

of paper and a space suitably indicated for indorsements on the remaining half of the front thereof, of a statement of account on 20 which the instrument is based on the reverse side of the sheet, means for sealing the edges of the two halves of the statement of account face to face, the statement of account being folded between the said check 25 and space for indorsements, and weakened lines within the said sealed edges.

Signed at Niles Ohio, this 7th day of February, 1913.

WENDELL D. MYRES.
